UNITED STATES PATENT OFFICE.

SWAIN PEARSON, OF ROCK ISLAND, ILLINOIS.

NECK-YOKE CENTER.

SPECIFICATION forming part of Letters Patent No. 629,868, dated August 1, 1899.

Application filed March 27, 1899, Serial No. 710,622. (No model.)

To all whom it may concern:

Be it known that I, SWAIN PEARSON, of Rock Island, Rock Island county, Illinois, have invented certain new and useful Improvements 5 in Neck-Yoke Centers, of which the following is a specification.

My invention relates to neck-yoke centers of that type embracing a clasp upon the neck-yoke bar and a band or collar on the tongue 10 and pivotally connected to the clasp, my object in this connection being to produce a device of this character which is efficient in use, adjustable to fit neck-yoke bars of varying 15 diameters, and of simple, strong, and durable construction and which may be placed on the market at less cost than analogous devices of equal strength and reliability.

To these ends the invention consists in certain novel and peculiar features of construction and combinations of parts, as will be hereinafter described and claimed; and in order that the invention may be fully understood reference is to be had to the accompanying drawings, in which—

Figure 1 represents a perspective view of a neck-yoke center embodying my invention. Fig. 2 represents a vertical central section of the same as secured upon the tongue and neck-yoke bar. Fig. 3 represents a front view 30 of the same. Fig. 4 is a view of the meeting edges of the clasp and the screws for clamping said edges together and to the neck-yoke bar.

In the said drawings, 1 designates a collar 35 to receive the customary metal tip 1^a of the tongue 1^b, said collar being provided with the customary leather lining, as shown at 2. The collar is also provided with an extension 3, projecting diagonally upward and rearward 40 from the upper side of the collar and formed at its upper and lower sides with circular bosses 4 and with a hole 5, extending centrally of said bosses.

Upon the neck-yoke bar 6 is secured the 45 clasp member of the neck-yoke center, said clasp member being, by preference, of ductile metal and formed in two semicircular sections or halves, the lower section being numbered 7 and the upper section 8. The lower section 50 is provided near its rear margin with the longitudinal slots 9, and the upper section

for a suitable distance from its rear edge or margin is diametrically increased in size, so as to provide in its under side the recess 10, wherein the rear edge of the lower section may 55 snugly fit, with its inner side flush with the inner side of the upper section, as shown clearly in Fig. 2. This extension or lip of the upper section is provided with oblique slots 11, which are adapted to register with 60 or intersect the longitudinal slots 9 of the lower section, screws 12 extending through said registering slots into the neck-yoke bar to secure said clasp-sections in such relation, as shown in Figs. 2 and 4. By the use of 65 these longitudinal and oblique intersecting slots it is obvious that the clasp may be diametrically increased or diminished, so as to fit neck-yoke bars of corresponding diameter—that is to say, when the center of the 70 oblique slots register with the longitudinal slots it is obvious that the clasp is of diameter to engage neck-yoke bars of intermediate size and that by causing the inner ends or the outer ends of the oblique slots to register 75 with the longitudinal slots the clasp will be diametrically diminished or increased, respectively, so as to fit smaller or larger neck-yoke bars, as will be readily understood.

13 designates parallel lugs projecting downward and forward from the center of the clasp-sections near their front margins and provided in their opposing or inner faces with circular sockets 14 to receive the circular bosses 4, hereinbefore described. 15 designates a bolt extending through said arms and the opening 5, and 16 a clamping-nut engaging said bolt to secure the clasp members reliably to the collar. By this arrangement it is obvious that the clasp operates pivotally 90 upon the circular bosses 4 of the collar without weakening the securing-bolt 15 by frictional contact with any other part. In other words, the bolt 15 is simply used as a securing-bolt and not as a pivot.

To relieve the securing-bolt 15 of any outward or tensile strain upon its head and threads applied by the arms 13 as levers fulcruming upon the neck-yoke bar, the clasp members at opposite sides of the arms 13 are 100 provided with parallel lugs 17, which are riveted firmly together, as shown at 18, or other-

wise reliably secured. These rivets relieve the bolt, as hereinbefore stated, of the strain imposed when the neck-yoke bar is slipped in or between the clasp-sections, and the latter are bent downward by insertion in a vise or in any other suitable manner, so as to conform to the exact curvature of the bar, the clasp-sections being of ductile metal, as hereinbefore suggested, so that this purpose may be readily effected. When bent tightly around the bar, they are secured by means of the screws 12, as hereinbefore explained.

From the above description it will be apparent that I have produced a neck-yoke center which embodies the features of advantage 15 enumerated as desirable in the statement of invention, and it will be further understood that I reserve the right to make all changes which properly fall within the spirit and scope 20 of the invention.

Having thus described the invention, what I claim as new, and desire to secure by Letters Patent, is—

1. A neck-yoke center, comprising a collar 25 mounted upon the tongue of a wagon, a split neck-yoke-bar clasp pivoted to said collar and embracing the neck-yoke bar, there being formed in one of the edges of said clasp longitudinal slots, and in the other edge of 30 the clasp oblique slots registering with the longitudinal slots, and securing devices ex-

tending through said registering slots into the neck-yoke bar, substantially as described.

2. A neck-yoke center, comprising a collar mounted upon the tongue of a wagon, a neck-yoke-bar clasp mounted upon the neck-yoke bar and pivoted to said collar, said neck-yoke bar consisting of two sections secured together at their front edges, one section being provided in its rear edge with a longitudinal 35 slot, and the other section with an oblique slot, the latter being adapted to register with the former, and a securing device, such as a screw, extending through said registering slots into the neck-yoke bar, substantially as 40 described.

3. In a neck-yoke center, a neck-yoke-bar clasp, consisting of two sections secured together at their front edges, one of the sections being provided with longitudinal slots 50 in its rear edge, the other being formed with a recess to receive the rear edge of the first-named section, said extension being provided with oblique slots adapted to register with said longitudinal slots, substantially as de- 55 scribed.

In testimony whereof I affix my signature in the presence of two witnesses.

SWAIN PEARSON.
